(57) **CLAIM**

The ornamental design for an illuminated light reflecting glove, as shown and described.

DESCRIPTION

FIG. 1 is a front view of an illuminated light reflecting glove embodying my new design, the glove shown with lighting elements not illuminated;

FIG. 2 is a rear view thereof;

FIG. 3 is a top view thereof;

FIG. 4 is a bottom view thereof;

FIG. 5 is a side view thereof as seen from the left-hand side of FIG. 1;

FIG. 6 is a side view thereof as seen from the right-hand side of FIG. 1;

FIG. 7 is a front view thereof with lighting elements illuminated;

FIG. 8 is a rear view thereof with lighting elements illuminated;

FIG. 9 is a top view thereof with lighting elements illuminated;

FIG. 10 is a side view thereof as seen from the left-hand side of FIG. 1 with lighting elements illuminated; and,

FIG. 11 is a side view thereof as seen from the right-hand side of FIG. 1 with lighting elements illuminated.

The illumination of the light-reflecting elements in FIGS. 1-3 and 5-11 is random.
